US0D1008559S

(12) **United States Design Patent** (10) **Patent No.:** **US D1,008,559 S**
(45) **Date of Patent:** **** Dec. 19, 2023**

(54) **PEDICURE DEVICE**

(71) Applicant: **E. MISHAN & SONS, INC.**, New York, NY (US)

(72) Inventor: **Mohan Rajasekaran**, Watertown, CT (US)

(73) Assignee: **E. MISHAN & SONS, INC.**, New York, NY (US)

(**) Term: **15 Years**

(21) Appl. No.: **29/899,863**

(22) Filed: **Aug. 14, 2023**

(51) LOC (14) Cl. **28-03**

(52) U.S. Cl.

USPC **D28/59**

(58) **Field of Classification Search**

USPC D28/56, 57, 58, 59; 132/73, 73.5
CPC A45D 29/00; A45D 29/11; A45D 29/14;
A45D 29/18

See application file for complete search history.

(57) **CLAIM**

The ornamental design for a pedicure device, as shown and described.

DESCRIPTION

FIG. 1 is a front, top left perspective view of a second embodiment of a pedicure device showing my design; FIG. 2 is a front elevational view of the same; FIG. 3 is a rear elevational view of the same; FIG. 4 is a left elevational view of the same; FIG. 5 is a right elevational view of the same; FIG. 6 is a top view of the same; and, FIG. 7 is a bottom view of the same.

The broken lines depict portions of the pedicure device that form no part of the claimed design.

1 Claim, 4 Drawing Sheets
